HOUSE

Donald D. Burris, Wayne, Pa., assignor to Certain-Teed Products Corporation, Ardmore, Pa., a corporation of Maryland

Filed Sept. 22, 1965, Ser. No. 87,123

Term of patent 14 years

(Cl. D13—1)

The dominant features of the design reside in the portions shown in full lines. The dominant features of the design are the multiple vertical lines of the posts and wall studs and the combination of those multiple vertical lines with the multiple horizontal lines of the jalousies, as included in both of the embodiments illustrated in the drawings.

I claim:

The ornamental design for a house, as shown and described.
